UNITED STATES PATENT OFFICE.

REINHOLD H. WEBER, OF ATHENS, OHIO, ASSIGNOR TO THE JEFFREY
MANUFACTURING COMPANY, A CORPORATION OF OHIO.

MINE-POST.

1,046,517.

Specification of Letters Patent. Patented Dec. 10, 1912.

Application filed February 4, 1911. Serial No. 606,579.

To all whom it may concern:

Be it known that I, REINHOLD H. WEBER, a citizen of the United States, residing at Athens, in the county of Athens and State 5 of Ohio, have invented certain new and useful Improvements in Mine-Posts, of which the following is a specification, reference being had therein to the accompanying drawing.

10 This invention relates to improvements in adjustable mine posts adapted for use in supporting the roof of a mine.

The object of the invention is to provide a strong, simple and cheap post of this character which is provided with means for adjustment through a wide range.

15 In the accompanying drawings, which form a part of this specification, I have shown the form of construction which I now deem preferable. However, numerous changes or modifications may be made without departing from the spirit of my invention.

20 Of the drawings Figure 1 is a side elevation. Fig. 2 is a vertical cross sectional view. Fig. 3 is a cross sectional plan view taken along the line 3—3 of Fig. 2.

25 Referring to the drawings, 1 and 2 represent the two main elements of the post, these elements being preferably tubular, with one telescoped within the other. The lower element 1 is preferably larger, the upper element 2 being of a size adapted to permit it to enter the element 1 with a free 30 working clearance. The ends of the elements 1 and 2 are provided with flanges 3 and 4 which serve to give increased bearing surfaces for contact with the mine floor and roof. The outer tubular element 1 is 35 provided with a plurality of pairs of opposite aligned apertures 5, 5 and 6, 6. Each of these apertures is preferably rectangular, ledges 7, 7 being formed on the outer part of the element 1 at the bottoms of the apertures to provide increased bearing surfaces 40 for the blocks and wedges to be hereafter described. The inner element 2 is similarly provided with a plurality of pairs of opposite aligned apertures 8, 8 and 9, 9. Differ-

45 ently viewed, the apertures 8, 8 or 9, 9 can be considered as a single aperture extending diametrically through the element 2. The upper surface of each combined pair of apertures is inclined, as shown in Fig. 2.

The apertures in the inner element 2 are 55 differently spaced from those in the outer element 1. As indicated, the distance between the apertures of the inner element is greater than that of the apertures of the outer element. However, so far as certain 60 features of my invention are concerned, this relation may be reversed, with the greater distance between the apertures of the outer element.

10 represents a wedge adapted to extend 65 through the apertures of both the outer element and the inner element. The upper surface of this wedge is beveled to have flat engagement with the inclined top surfaces of the apertures of the inner element. 70

11, 11 are filler blocks which are provided with depending lugs 12, 12, adapted to engage the edges of the ledges 7, 7, or notches 13, 13, in a similar filler block to prevent endwise movement. 75

In operation, the two main elements of the post after being placed one within the other, are adjusted to approximately their final positions. Then the wedge 10 is inserted through those apertures which are in 80 properly related positions to permit the action of the wedge. After the wedge is inserted, it is driven in by a sledge to force the telescoping elements into firm and final engagement with the mine floor and roof. 85 For certain positions no filler blocks are needed. For other positions, one may be necessary, and in still others, two. It will be apparent that on account of the differential spacing of the apertures of the two 90 elements, the elements can be locked in any one of a wide range of relative positions.

It will be obvious that additional sets of apertures may be added if desired, the same differential spacing being maintained. Furthermore, my invention is not limited to two 95 filler blocks as shown, as by properly proportioning the apertures and the wedges and blocks, any desired number of blocks can be used. 100

While I have described my invention as an adjustable post for supporting mine roofs, it will be obvious that it is not necessarily so limited, but may also be used as a support in various other connections, and 105 also as a jack for heavy hoisting.

What I claim is:

1. The combination in a device of the class

described, of two telescoping elements each provided with a through diametrical aperture, a plurality of filler blocks adapted to be placed one upon another within the apertures with one of them in engagement with the outer element, means for locking all of the blocks against endwise movement, and a wedge adapted to be inserted through the apertures adjacent the blocks to move one of the said elements longitudinally relatively to the other.

2. The combination in a device of the class described, of two telescoping elements each provided with a through diametrical aperture, a plurality of filler blocks adapted to be placed one upon another within the apertures, each block having lugs adapted to engage either the outer element or another block to prevent endwise movement, and a wedge adapted to be inserted through the apertures adjacent the blocks to forcibly move one of the said elements longitudinally relatively to the other.

3. The combination in a device of the character described, of two telescoping elements, a plurality of through diametrical apertures in each, the longitudinal spacing of the apertures of one element being different from that of the other element, and means adapted to engage the edges of any set of apertures to cause the longitudinal

movement of one element longitudinally relatively to the other.

4. The combination in a device of the character described, of two elements one 35 slidable relative to the other and each provided with a plurality of through diametrical apertures, the apertures of one element being differently spaced longitudinally from those of the other, and a wedge adapted to be inserted through any set of apertures of the two elements to forcibly move one of the said elements longitudinally relatively to the other.

5. The combination in a device of the 45 character specified, of two elements, one slidable relative to the other, a plurality of spaced ledges on one element, a plurality of differently spaced ledges on the other, and means for engaging any ledge of one element and any ledge of the other to lock one element against longitudinal movement relative to the other in one direction and to forcibly move it relatively to the other in the other direction.

In testimony whereof I affix my signature, in presence of two witnesses.

REINHOLD H. WEBER.
